BLOW-OUT PREVENTER

Melvin C. Inge, Brea, Calif.

Application May 25, 1937, Serial No. 144,647

12 Claims. (Cl. 251—57)

This invention relates to a device for use on wells such as oil wells and gas wells and relates more particularly to a blowout preventer for controlling a well during the drilling operations.

5 A general object of this invention is to provide a blowout preventer that is simple and practical and that is positive and dependable in operation.

During the drilling of deep wells such as oil wells and gas wells high fluid pressures are frequently encountered in the earth formation penetrated by the drilling tools. This pressure often develops very rapidly and blows out through the well around the drilling tools sometimes causing considerable damage. Control devices known 15 as blowout preventers have been introduced for application to the upper ends of the well casings for controlling the high pressures that may suddenly develop in the well when the drilling tools are in the well.

20 Another object of this invention is to provide a blowout preventer embodying closure members or gates that may be quickly and readily operated into the well casing opening to seal about the drill pipe and thus control the well when high pressures develop in the well.

25 Another object of this invention is to provide a blowout preventer in which the gates are constructed and arranged so that the fluid pressures in the well tend to urge the gates into more effective sealing cooperation with the drill pipe and the seat of the blowout preventer body.

Another object of this invention is to provide 30 a blowout preventer embodying novel and very dependable means for actuating or forcing the gates into sealing cooperation with the body seat and the drill pipe in such a manner that the well pressures may tend to maintain the fluid tight sealing engagement of the gates with the pipe and body seat.

40 Another object of this invention is to provide a blowout preventer of the character mentioned in which the gates may be quickly and easily removed from the body for the purpose of repair or for replacing the packing means.

45 Another object of this invention is to provide a blowout preventer of the character mentioned in which the gates may be removed through relatively small openings in the sides of the body whereby the body may be simple and inexpensive 50 in construction and light in weight.

55 A further object of this invention is to provide a blowout preventer that embodies novel and particularly effective sealing means or packing means on the control gates.

55 The various objects and features of my inven-

tion will be fully understood from the following detailed description of typical preferred forms and applications of my invention, throughout which description reference is made to the accompanying drawings, in which:

Fig. 1 is a vertical detailed sectional view of the improved blowout preventer provided by this invention illustrating the gates in elevation in the closed positions and with broken lines illustrating the retracted positions of the gates. Fig. 10 5 Fig. 2 is a fragmentary detailed sectional view taken substantially as indicated by line 2—2 on Fig. 1 illustrating one of the nuts and the adjacent parts. Fig. 3 is a horizontal detailed sectional view taken substantially as indicated by line 3—3 on Fig. 1 with certain parts of the gates broken away to appear in horizontal cross section. Fig. 4 is a perspective view of one of the gates removed from the body. Fig. 5 is a vertical detailed sectional view 10 of one of the gates removed from the device, being a view taken as indicated by line 5—5 on Fig. 3. Fig. 6 is a top view of a 15 gate that may be employed in the blowout preventer and that employs a modified form of packing means and Fig. 7 is a fragmentary vertical 20 detailed sectional view taken as indicated by line 7—7 on Fig. 6.

The blowout preventer of the present invention comprises, generally, a body 10 to be connected with a well casing C, closure members 30 or gates 11 movable in the body 10, means 12 for moving or actuating the gates 11 and packing means 13 on the gates 11 for sealing with the body 10 and an object or pipe P extending through the body 10. 35

The body 10 is adapted to be applied to or connected with the upper end of a well casing C and is such that the various drilling tools may be passed into and out of the casing without difficulty when the gates 11 are in the retracted positions. The body 10 constitutes a housing or casing and is a hollow member or structure. A substantially vertical opening 14 extends through the body 10 and is intended to form a continuation of the opening of the casing C. A means is 40 provided at the lower end of the opening 14 to facilitate the connection of the body 10 with the casing C. In the simple case illustrated the lower portion of the body opening 14 is internally threaded to receive the threaded upper portion 45 of the casing C. The upper portion of the opening 14 may be internally threaded to receive the threaded parts of a nipple or casing extension. In accordance with the invention the body 14 has 50 a transverse chamber 15 intersecting the opening 55

14. The chamber 15 is generally rectangular and is defined by substantially horizontal upper and lower body walls 16, substantially vertical outer body walls 17 and substantially vertical body side walls 18. The several walls 16, 17, and 18 may be integral with the remainder of the body 10. The chamber 15 is provided to contain the gates 11 and is proportioned so that the gates may be entirely retracted from the opening 14 to permit the 10 passage of drilling tools through the casing C.

Access openings or service openings 19 are provided in the side walls 18. In practice it is necessary to provide openings 19 in only one side wall 18. In the particular construction illustrated 15 there are two openings 19 in each wall 18. The openings communicate with the sides of the outer portions of the chamber 15. Covers or plates 20 normally close the openings 19. Screws 21 may 20 removably secure the plates 20 to the body 10 to normally close the openings 19. In accordance 25 with the invention a sealing surface or seat 22 is provided on the interior of the body 10 around the opening 14 to be engaged by the gates 11 and their packing means 13. The seat 22 is annular and completely surrounds the body opening 14 at the juncture of the upper wall of the chamber 15 with the opening 14. The seat 22 is 30 conical or partially conical and slopes downwardly and outwardly with respect to the central vertical axis of the opening 14.

The closure members or gates 11 are shiftable transversely or horizontally in the chamber 15 between positions entirely clear of the opening 14 and positions where they extend across the 35 opening 14 and engage about the pipe P. There are two gates 11 arranged at opposite sides of the central vertical axis of the device. The gates 11 are alike or complementary and in practice may be substantially rectangular or block-like in 40 shape. In the construction illustrated the gates 11 have flat parallel upper surfaces 23 and lower surfaces 24 and flat parallel side surfaces 25. The inner sides or opposing sides of the gates 11 45 may be flat and vertical and carry the packing means 13 as will be subsequently described. The vertical dimensions and the horizontal dimensions in both directions of the gates 11 are considerably smaller than the corresponding dimensions of the chamber 15.

50 A vertical partially cylindrical groove 26 is provided on the inner or active side of each gate 11. The grooves 26 register to receive the pipe P when the gates are operated inwardly or toward one another. A raised boss 27 is provided 55 on the upper side 23 of each gate 11. The bosses 27 are substantially semi-circular and are concentric with the grooves 26. The outer or peripheral surfaces of the bosses 27 are in the 60 nature of sealing faces 28 and are adapted to cooperate with or oppose the seat 22 when the gates 11 are in their active or closed positions. The faces 28 are conical or partially conical and are 65 adapted to evenly cooperate with or conform to the seat 22. The gates 11 may be cored out or recessed from their outer sides as at 29 to reduce their weight and cost.

70 The means 12 for actuating the gates 11 is an important feature of the invention. In accordance with the invention the means 12 is operable to move the gates 11 inwardly toward one another and at the same time shift the gates upwardly to bring the faces 28 in contact with or conformity to the seat 22 in such a manner that the upward 75 force exerted by the fluid pressure in the casing

C may tend to more tightly urge the gates against the seat. The means 12 includes cooperable inclined surfaces or cam surfaces on the body 10 and the gates 11. Inclined surfaces 30 are provided on the lower wall 16 of the chamber 15 at 5 opposite sides of the body opening 14. The surfaces 30 are inclined downwardly and outwardly with respect to the vertical axis of the opening 14 and are of the same pitch and are equally spaced from the axis of the opening 14. The body surfaces 30 are of the same pitch or of substantially the same inclination as the conical body seat 22. The inclined surfaces 30 may be of substantial length and may extend between the opposite side walls 18 of the body. The body 10 may be thickened to present the surfaces 30 and the thickened portions of the body may present horizontal or transverse upwardly facing surfaces 31 which extend inwardly from the surfaces 30 to the wall of the body opening 14. 10

20 The gates 11 are provided with tails or downwardly projecting parts 32 at their outer ends. The parts 32 project downwardly from the lower sides 24 of the gates and their rear sides may be flush with the rear sides of the gates. Downwardly and outwardly inclined surfaces 33 are provided on the inner sides of the parts 32 to cooperate with the body surfaces 30. The surfaces 33 are of the same pitch or inclination as the surfaces 30 and are of substantially the same 30 vertical extent as the surfaces 30. The lower ends 34 of the parts 32 are flat and substantially horizontal and are adapted to rest on the bottom wall 16 of the chamber 15 when the gates 11 are in their retracted positions. 35

When the gates 11 are moved inwardly toward the drill pipe P the surfaces 33 come into contact with the surfaces 30 and the cooperation of the surfaces 33 and 30 cams or shifts the gates 11 upwardly and inwardly. The parts are related 40 so that this compound movement or upward and inward movement of the gates 11 brings the sealing surfaces 28 into conformity or cooperation with the body seat 22. Thus the cam surfaces 30 and 33 of the means 12 are operable to 45 direct the gates 11 upwardly and inwardly against the seat 22 in such a manner that the force or pressure exerted by the fluid pressure in the casing C may tend to urge the faces 28 into tighter engagement with the seat 22. 50

The gate actuating means 12 further includes a mechanism for moving the gates 11 toward and away from the longitudinal axis of the body opening 14. In the preferred construction illustrated in the drawings this mechanism is in the 55 form of a screw means. As illustrated in the drawings screws S extend horizontally through the body chamber 15. The screws S have their opposite end portions rotatably supported by the body end walls 17 and are preferably supported 60 between their ends. In the preferred form of the invention there is a screw S extending horizontally through the chamber 15 adjacent each side wall 18 so that the screws S are adjacent the sides 25 of the gates 11. 65

It is preferred to construct each screw S of two sections 35 and 36, one section of each screw S having a right-hand thread and the other section of each screw having a left-hand thread. The outer portions of the screw sections 35 are 70 rotatably supported in sockets 37 in plugs 38. The plugs 38 are threaded in openings 39 in the end body walls 17. The plugs 38 may carry thrust bearings in the form of balls 40 cooperat- 75 ing with the ends of the screw sections 35. The 75

outer portions of the screw sections 36 are rotatably supported in openings 41 in the other end wall 17. Flanges 42 may be provided on the screw sections 36 to engage against shoulders in the openings 41 to limit the inward movement of the screw sections 36. Socket members 43 are arranged in the openings 41 to surround the screw sections 36 and bear inwardly against the flanges 42. The members 43 are removably secured to the body 10 by studs or screws 44. Packing glands 45 are carried by the socket members 43 to seal about the screw sections 36.

Releasable driving connections are provided between the inner or opposing ends of the sections 35 and 36 of each screw S. The inner ends of the screw sections 36 have polygonal sockets 46 and the sections 35 have polygonal end portions 47 cooperating with the sockets 46 for the transmission of rotation between the sections.

20 The releasably coupled inner ends of the screw sections 35 and 36 are rotatably supported by bearing means. Bearing pins 48 are passed inwardly through openings 49 in the body walls 18. The pins 48 have flanges 50 seating inwardly against shoulders in the openings 49. Plugs 51 are threaded in the openings 49 to clamp inwardly against the pins 48 and retain them in position. Transverse or diametric openings 52 are provided in the inner portions of the bearing pins 48. The inner or connected portions of the screw sections 35 and 36 are cylindrical and without threads and are rotatably supported in the openings 52 of the bearing pins 48. In this manner the bearing pins 48 rotatably support the screws S at points between their ends.

The screws S are operatively interconnected to be turned or rotated in unison. A sprocket 53 is fixed to the projecting outer portion of each screw section 36 and a chain 54 operates over the sprockets 53 to connect the two screws S for simultaneous rotation. The screws S may be driven or rotated in any suitable manner, for example, they may be rotated by hand, by an electric motor, by an engine, or any other source of power. The outer portion 55 of one or both of the screws S may be polygonal to facilitate the connection of a power source with the screw or screws.

50 The gate actuating means 12 further includes nuts N threaded on the screws S and shiftably associated with the gates 11 to effect the movement of the gates into and out of cooperation with the pipe P. Grooves 54 are provided in the opposite sides 25 of the gates 11 to cooperate with or partially receive the nuts N. The grooves 54 may have flat substantially vertical inner walls and flat parallel side walls 54a. The grooves 54 are inclined, that is, their side walls 54a are inclined downwardly and inwardly relative to the longitudinal axis of the body opening 14. The several grooves 54 have the same degree of inclination. The grooves 54 preferably extend between the upper and lower ends of the gates 11.

65 A nut N is provided for cooperating with each groove 54, there being a nut N on each screw section 35 and 36. In accordance with the invention the nuts N are sectional to permit the easy removal of the gates 11 from the body 10. The nuts N each include an inner section 55 and an outer section 56. The inner sections 55 are substantially rectangular block-like parts and the outer sections 56 are block-like members arranged against the sections 55. Inwardly extending flanges 57 are provided at the opposite

ends of the outer sections 56 and engage or cover the ends of the inner sections 55. Screws 58 are passed through openings 59 in the outer sections 56 and are threaded in sockets 62 in the inner sections 55 to detachably connect the nut sections. The heads of the screws 58 are countersunk in the openings 59. The nuts N are elongate and are partially received in their respective grooves 54 with their greatest dimensions extending longitudinally of the grooves. The 10 end surfaces of the flanges 57 of the outer sections 56 slidably cooperate with the side walls 54a of the grooves while the sections 55 may be clear of the grooves. The nuts N are of greater depth or thickness than the grooves 54 and project from the grooves to have the outer surfaces of the sections 56 adjacent to or in sliding cooperation with the side walls 18 of the chamber 15. This engagement of the nuts N with the walls 18 of the chamber 15 guides the gates 11 20 and prevents lateral shifting of the gates.

As mentioned above, the nuts N are threaded on the screws S. The inner sections 55 of the nuts N have tube halves 60 inset in their outer surfaces and the outer nut sections 56 have complementary tube halves 60 inset in their inner surfaces to oppose the tube halves 60 on the inner sections. The tube halves 60 of the nut sections 55 and 56 are related to constitute tubes for receiving the screws S and in the preferred construction they are of sufficient length to project beyond the opposite sides of the nuts N to have substantial engagement with the screws S. The tubes formed by the halves 60 are internally threaded and their threads cooperate with the 30 threads of the screw sections 35 and 36. The tube halves 60 may be welded to their respective nut sections 55 and 56, it being understood that they may be formed integral with the sections, if desired. The opposite sides of the nuts N may 40 have suitable slight clearance with the side walls 54a of the grooves 54.

Upon rotation of the screws S the threads of the screw sections 35 and 36 and the tube halves 60 cooperate to effect retraction or advancement of 45 the gates 11 depending upon the direction of rotation of the screws. In the case of the advancement of the gates 11 toward the pipe P the nuts N cooperating with the inclined grooves 54 tend to wedge or shift the gates 11 upwardly as well as 50 horizontally. The bosses 27 cooperating with the upper wall of the chamber 15 prevent this upward movement of the gates throughout the initial portion of their movement. However, when the upper edges of the boss faces 28 reach the 55 lower edge of the seat 22 the gates 11 may move upwardly as well as horizontally. At this time the surfaces 33 come into engagement with the surfaces 30 and their cooperation with the surfaces 30 cams or shifts the gates 11 upwardly and 60 inwardly with respect to the longitudinal axis of the opening 14. Thus when the screws S are rotated to actuate the gates 11 the gates are moved inwardly toward one another and then upwardly and inwardly toward one another, as they approach the pipe P.

65 The packing means 13 is provided to assure a fluid-tight engagement of the gates 11 with the pipe P and the seat 22 and a fluid-tight cooperation of the active sides of the gates when the 70 gates are actuated into engagement. The seat engaging faces 28 of the gates 11 are provided with grooves 63. The grooves 63 are spaced between the upper and lower edges of the faces 28 and are curved concentric with the faces. In the 75

case illustrated the grooves 63 are rectangular in cross section it being understood that they may be dove-tailed if desired. A relatively narrow lip or ridge 64 may project from the inner or active face of each gate 11. The ridges 64 extend along the margins of the inner faces of the gates and continue along the faces of the gates at the upper and lower ends of the grooves 26. In the form of the invention illustrated in Figs. 1 to 4, inclusive, of the drawings, the packing 13 comprises an integral body 65 of packing material covering the active face of each gate 11 and occupying the groove 63 of its respective gate.

The packing bodies 65 may be formed of rubber or other suitable packing material and are shaped to conform to the inner faces of the gates 11 and to occupy the grooves 63. In the preferred construction the packing bodies 65 completely cover the inner surfaces of the gates 11. Where the gates 11 are provided with the ridges 64 as described above, the packing bodies 65 have shoulders 66 bearing against the inner sides of the ridges 64 and the bodies extend over or cover the outer faces of the ridges. Screws 67 or other suitable securing members may attach the packing bodies 65 to the gates 11.

A strap or strip 68 is integrally joined with each packing body 65 adjacent one of its upper outer corners and curves outwardly or rearwardly and then inwardly to its other upper corner to occupy the groove 63 of the gate. The free ends of the strips 68 are folded across the faces of the packing bodies 65 and may be secured to the gates 11 by screws 69. The portions of the straps 68 lapped over the packing bodies 65 may be inset or recessed in the packing bodies. Pins 70 may be passed through spaced openings in the bosses 27 and the strips 68 to assist in retaining the strips in the grooves 63. The strips 68 preferably project slightly from the grooves 63 to better seal with the seat 22. It will be observed that the packing bodies 65 completely cover the active inner sides of the gates 11 and the grooves 63 to fully seal with the pipe and the seat 22 and to seal one against the other when the gates are in the closed positions. There are no seams or joints in the packing bodies 65 to permit the escape of fluid under pressure.

During the drilling operations the gates 11 are normally in their out or retracted positions indicated by the broken lines in Fig. 1 of the drawings. When in these positions the gates 11 are completely clear of the opening 14 and, therefore, do not interfere with the operation or passage of the drilling tools through the casing C. In the event that heavy pressures suddenly develop in the well the screws S are rotated in a direction to actuate the gates 11 inwardly. The threads of the screw sections 35 and 36 and the tube halves 60 cooperate to feed the nuts N inwardly along the screws. The inwardly moving nuts N cooperate with the grooves 54 to force the gates 11 inwardly toward one another. During the initial inward movement of the gates 11 the upper sides 65 of the bosses 27 may engage the upper wall of the chamber 15 to prevent upward movement of the gates. When the upper margins of the faces 28 reach the lower margin of the seat 22 the gates 11 may move upwardly as well as inwardly. At this time the surfaces 33 come into camming engagement with the surfaces 30. This cooperation of the surfaces 33 with the surfaces 30 coupled with the cooperation of the nuts N with the inclined walls 54 of the grooves 54 effects the upward and inward movement of the gates 11.

This movement of the gates 11 is, of course, simultaneous. The upward and inward movement of the gates 11 continues until the faces 28 are in conformity with the seat 22 at which time the strips 68 may tightly seal against the seat. The surfaces 33 remain in engagement with the surfaces 30 when the gates 11 reach this position.

When the faces 28 are in conformity with the seat 22 the inner sealing surfaces of the packing bodies 65 are in cooperation and the concave parts of the packing bodies occupying the grooves 26 are in sealing engagement with the pipe P. Further turning force applied to the screws S may tend to bring the packing bodies 65 into tighter cooperation and into tighter sealing engagement with the pipe P and may further compress the strips 68 against the seat 22. The upward fluid pressures in the casing C are, of course, exerted against the lower ends of the gates 11 which close off the opening 14. The force or pressure exerted by the fluid under pressure in the casing C merely tends to force the gates 11 into tighter cooperation with the seat 22 and tends to force the gates inwardly toward one another to more tightly pack about the pipe P. The cooperation of the inclined walls 54 with the nuts N brings about this inward wedging of the gates 11 one against the other under the action of the well pressures. For this reason the gates 11 wedged one against the other and wedged against the pipe P and the seat 22 dependably and effectively seal off the well. Closing of the casing C by the gates 11 of course brings the well under control.

The gates 11 may be easily retracted from the opening 14 by merely rotating the screws S. During the initial outward movement of the gates 11 the faces 28 or the strips 68 or both cooperate with the seat 22 to cam the gates downwardly and downwardly. At this time the surfaces 33 slide downwardly and outwardly on the surfaces 30. This may bring the ends 34 in engagement with the bottom wall of the chamber 15 and the lower surfaces 24 into engagement with the shoulder 31, at which time the downward movement of the gates is stopped. Further rotation of the screws S to retract the gates 11 results in outward movement of the gates to their retracted positions illustrated by the broken lines in Fig. 1.

When it becomes necessary or desirable to inspect or replace the packing bodies 65 on the gates 11 the plates 20 at one side of the body 10 are removed. Upon removal of a plate 20 the screws 58 of the adjacent nut N are accessible for engagement by wrenches and may be easily unscrewed so that the outer nut section 56 may be removed. Following the removal of the outer nut section 56 the inner section 55 is moved inwardly to disengage its thread portion from the thread of the screw section 35 or 36. The nut N accessible at the other uncovered opening 19 is treated in a like manner. This disengages the nuts N from one of the screws S. The plug 38 at the end of that screw is removed whereupon the screw section 35 may be withdrawn from the body 10. The socket member 43 at the other end of the screw S is then removed from the body whereupon the screw section 63 may be withdrawn from the body. Upon the removal of the screw S the two gates 11 may be individually withdrawn outwardly through the openings 19. As the nuts N at the other side of the device are not permanently secured to the gates the gates may be merely moved laterally out of engagement with the nuts remaining in the body. In this manner the gates 75

11 may be easily removed from the body for inspection, repair, etc. It is believed that it will be understood how the gates may be inserted in the body and the several parts reassembled to condition the blowout preventer for further use.

15 Figs. 6 and 7 illustrate a gate 11^a having a slightly modified form of packing means 13^a. The gate 11^a is of the full shut-off type; that is, two gates 11^a of the character illustrated in Figs. 10 6 and 7 may be employed in place of the gates 11 to control the well when the string of pipe P is withdrawn from the well or is not extending through the blowout preventer. It is to be understood that the packing means 13 and 13^a may be 15 employed on either form of gate 11 or 11^a.

The gate 11^a is substantially identical with the gate 11 described above except that its inner face is flat and devoid of the groove 26. The inner or active face of the gate 11^a may have a ridge 20 similar to the above described ridge 54 which ridge may extend along the entire margin of the inner face of the gate. The sealing face 28^a of the gate 11^a may be similar to the sealing face 28 and is provided to cooperate with the seat 22 25 of the body 10. A curved elongate depression or groove 63^a is provided in the face 28^a. The groove 63^a is V-shaped in cross section, having two walls converging outwardly to the face 28^a, one wall being substantially vertical and the 30 other being substantially horizontal. The groove 63^a is spaced between the upper and lower margins of the face 28^a and extends between the 35 opposite ends of the face.

The packing means 13^a illustrated in Figs. 6 40 and 7 includes a packing body 65^a covering the active inner face of the gate 11^a and a strip or 45 loop 68^a for fitting the groove 63^a. The packing body 65^a preferably covers the entire inner face 50 of the gate 11^a and is preferably one piece or integral. The loop 68^a has its opposite ends integrally joined with the packing body 65^a and 55 curves outwardly or rearwardly from the packing body 65^a at its upper end to fit the groove 63^a. The loop 68^a is triangular shaped in transverse cross section, having inwardly convergent sides 60 cooperating with the walls of the groove 63^a and having a flat outer surface for cooperating with or sealing against the body seat 28. The 65 loop 68^a may be sprung into the groove 63^a when the packing means is assembled on the gate 11^a and may be secured in place by pins 70^a arranged in openings in the gate 11^a to pass through openings in the loop 68^a. The packing body 65^a and 70 its loop 68^a are readily removable for replacement when worn. The gate 11^a illustrated in 75 Figs. 6 and 7 has substantially the same function and operation as the gates 11 described above.

Having described only typical preferred forms 80 and applications of my invention, I do not wish to be limited or restricted to the specific details herein set forth, but wish to reserve to myself any variations or modifications that may appear to those skilled in the art or fall within the scope 85 of the following claims.

Having described my invention, I claim:

1. A blowout preventer for use on a well casing 90 comprising a body having an opening for registering with the opening of the casing, a seat 95 in the body around the body opening, shiftable gates in the body, means for moving the gates toward one another in a direction transverse of the longitudinal axis of the body opening to engage about an object in the body opening, and 100 means for shifting the gates upwardly during

their inward movement to engage against the seat.

2. A control device for use on a well casing including a body having an opening in communication with the interior of the casing, a substantially downwardly facing seat in the body around the opening, movable gates in the body, means for moving the gates inwardly toward the opening in a plane substantially normal to the longitudinal axis of the opening to seal with one another and engage about an object in the opening, and means for shifting the gates upwardly during their inward movement to engage against the seat, the last mentioned means including 15 cooperable cam faces on the body and the gates. 15

3. A control device for use on a well casing including a body having an opening in communication with the interior of the casing, a substantially downwardly facing seat in the body around the opening, movable gates in the body, means for moving the gates inwardly toward the opening in a plane substantially normal to the longitudinal axis of the opening to seal with one another and engage about an object in the opening, and means for shifting the gates upwardly during 20 their inward movement to engage against the seat, the last mentioned means comprising inclined faces in the body facing outwardly with respect to the opening, and inclined faces on the gates facing inwardly with respect to the opening 25 and cooperable with the first mentioned faces. 30

4. A control device for use on a well casing including a body having an opening in communication with the interior of the casing, a downwardly facing seat in the body around the opening, movable gates in the body, means for moving the gates inwardly toward the opening in a direction at substantially right angles to the opening, and cam means for shifting the gates upwardly against the seat during their inward 40 movement. 35

5. A control device for use on a well casing including a body having an opening in communication with the interior of the casing, a downwardly facing seat in the body around the opening, movable gates in the body, screw means for moving the gates inwardly toward the opening in a direction at substantially right angles to the opening to seal with one another, and cam means for shifting the gates upwardly against the seat during 50 their inward movement. 45

6. A control device for use on a well casing including a body having an opening in communication with the interior of the casing, a downwardly facing seat on the interior of the body around the opening, movable gates in the body, rotatable screws carried by the body, nuts having threaded engagement with the screws and shiftably cooperating with the gates to move them inwardly into the opening to seal with one 60 another when the screws are rotated, and cam parts on the gates and body cooperable to shift the gates against the seat during the inward movement of the gates. 55

7. A control device for use on a well casing including a body having an opening in communication with the interior of the casing, an inclined seat on the interior of the body around the opening, movable gates in the body having inclined surfaces pitched in the opposite direction to the 70 seat, means for moving the gates inwardly toward the central longitudinal axis of the opening to bring the gates into sealing cooperation comprising actuating parts cooperating with the said inclined surfaces, and cam means for shifting the 75

gates upwardly on the actuating parts during inward movement of the gates to bring the gates against the seat.

8. A control device for use on a well casing including a body having an opening in communication with the interior of the casing, a downwardly facing seat on the interior of the body around the opening, movable gates in the body having grooves inclined upwardly and outwardly with respect to the longitudinal axis of the opening, nuts shiftably cooperating with the grooves, screws actuating the nuts to shift the gates inwardly with respect to the longitudinal axis of the opening, and cooperable cam parts on the body and gates operable to shift the gates upwardly on the nuts to engage the seat.

9. A control device for a well casing comprising a body having an opening in communication with the interior of the casing and a chamber intersecting the opening, gates shiftable in the chamber, a downwardly facing inclined seat on the interior of the body around the opening, screws extending through the chamber, inclined grooves in the sides of the gates, nuts threaded on the screws and shiftably cooperating with the grooves whereby rotation of screws in one direction effects inward movement of the gates toward the axis of the opening, and cooperable inclined surfaces on the body and gates for shifting the gates upwardly relative to the nuts to engage the seat.

10. A control device for a well casing comprising a body having an opening in communication with the interior of the casing and a chamber intersecting the opening, gates shiftable in the chamber, a downwardly facing inclined seat on the interior of the body around the opening, screws extending through the chamber, nuts on the screws cooperating with the gates, means for rotating the screws to shift the gates into and out of the opening, each nut including sections, and means detachably securing together the sections, the sides of the body having access openings rendering the detachable securing means accessible

and adapted to pass the gates upon disconnection of the nut sections, and means supporting the screws for removal from the body.

11. A control device for a well casing comprising a body having an opening in communication with the interior of the casing and a chamber intersecting the opening, gates shiftable in the chamber, a downwardly facing inclined seat on the interior of the body around the opening, screws extending through the chamber, means supporting the end portions and the intermediate portions of the screws for rotation, nuts threaded on the screws and having cooperation with the opposite sides of the gates to effect their movement into and out of the opening, means interconnecting the screws for simultaneous rotation, and cam means for shifting the gates upwardly against the seat when the gates are moved inwardly by the nuts.

12. A control device for a well casing comprising a body having an opening in communication with the casing, a chamber intersecting the opening and access openings in a side wall of the chamber at opposite sides of the opening, a seat on the interior of the body around the opening, gates shiftable in the chamber, cam means for moving the gates against the seat during shifting of the gates into the opening, and means for shifting the gates comprising screws passing through the chamber, each screw including two sections, means removably supporting the opposite ends of the screws and permitting removal of the sections of the screws from the ends of the chamber, sectional nuts threaded on the screws and shiftably cooperating with the gates to move the same, and means for rotating the screws to shift the gates, the nuts including sections, and means detachably connecting the nuts sections manipulable through said access openings whereby the nuts may be released from the screws to permit removal of the screws and removal of the gates through the access openings at right angles to the screws.

MELVIN C. INGE.
